L. L. WITTER

WHEELED FIGURE TOY

Filed April 18, 1927

UNITED STATES PATENT OFFICE.

LAWRIE L. WITTER, OF BROOKLINE, MASSACHUSETTS.

WHEELED-FIGURE TOY.

Application filed April 18, 1927. Serial No. 184,727.

This invention relates to toys and more especially to wheeled figure toys. It is well known that a moving figure toy which simulates the movements and sounds of the figure animal in life is most attractive. Furthermore, a child is more especially delighted with a figure toy in which he can cause different movements and sounds at will. It is therefore the primary object of my invention **10** to provide a figure toy constructed to be operated in this manner.

It is a further object of my invention to provide a wheeled figure toy of the above type and means whereby the said different **15** movements and sounds of the toy are optionally controlled from the means by which the toy is moved along.

More specifically my figure toy embodies a pair of rollers and a cooperating movable **20** weight whereby one or the other of the rollers can be brought into supporting engagement in a manner optionally operating mechanisms connected to the rollers, the location of the weight preferably being controlled by **25** the means by which the toy is moved.

In the accompanying drawing I have illustrated certain specific embodiments of my invention but it will be understood that the invention can be otherwise embodied and that **30** the drawing is not to be construed as defining or limiting the scope of the invention, the claims appended hereto being relied upon for that purpose.

Referring to the figures of the drawing, **35** Fig. 1 is a side elevation of one embodiment of my invention.

Fig. 2 is a bottom plan view thereof.

Fig. 3 is a fragmentary cross section taken on line III—III of Fig. 1.

Fig. 4 is a cross section taken on line IV—IV of Fig. 1.

Fig. 5 is a vertical longitudinal section therethrough.

Fig. 6 is a view like Fig. 5 but showing a **45** modification of the invention.

Referring first to Figs. 1 to 5 of the drawing, 1 indicates the body portion of the toy. This body is preferably made of wood and may be a duck, as illustrated, or any animal

or figure desired. The body is supported on **50** a pair of rollers 2 adapted to ride on a support 3. These rollers are centrally disposed whereby they normally balance the weight of the body.

The under side of the front portion of the **55** body is chambered to receive a roller 4 and a pair of cranks 5 on the ends of a shaft 6 secured to the roller. I have illustrated these cranks as adapted to flap the wings 7. Each **60** wing 7 is supported on a pair of arms 8 mounted on a shaft 9. One arm 10 of each pair extends inwardly as shown in Fig. 4 and is counterbalanced by a spring 11 in a manner rendering the flapping operation very easy. A link 12 connects each crank 5 to its respective arm 10. Obviously when the **65** roller 4 is rotated the wings 7 are caused to flap.

The under side of the rear portion of the **70** body is chambered in like manner to receive a roller 13 and a pair of cranks 14 on the ends of a shaft 15 secured to the roller. I have illustrated these cranks as adapted to move the feet 16 to simulate swimming. The **75** feet are preferably made large and broad and are carried on legs 17 pivoted to a shaft 18. The cranks operate in slots in the legs as the roller 13 rotates and oscillate the legs as will be understood. It should be particularly noted that the body 1 is so chambered **80** that only the broad feet 16 are seen, the roller 13 and other operating mechanism being hidden.

A bore 19 is formed longitudinally in the **85** back of body 1 directly over the axis of the supporting rollers 2 and a weight 20 is mounted to slide in this bore. When the weight is in the position illustrated in Fig. 5 the roller 13 will rest on the support 3 and movement of the duck will rotate this roller **90** and move the feet 16 to simulate swimming. When the weight is moved to the front end of the bore 19 the roller 4 will rest on the support 3 and movement of the duck will rotate this roller and flap the wings to simulate **95** flying.

I also prefer to control the position of the weight 20 by the means which moves the toy.

As illustrated, the duck is drawn along by a double cord 21. The top cord is attached to the front of the weight and the bottom cord is attached to the rear of the weight and extends about a sheave 22. Pulling the duck by means of the top cord shifts the weight forwardly and causes the wings to flap and pulling the duck by means of the bottom cord shifts the weight rearwardly and causes the duck to swim.

In Fig. 6 I show a slightly modified form of my invention. In this illustration one end 23 of the body is made in the form of a duck and the other end 24 is made in the form of a chicken. The body is balanced on rollers 25 and cooperating rollers 26 and 27 are provided. The roller 26 is connected to and adapted to operate a noise making device such as a bellows 28 which produces a duck's "quack". The roller 27 has a notched portion 29 on which rides a spring member 30 which produces a chicken's "cackle". A weight 31 like the weight 20 is adapted to control the position and operation of the toy. Cords 32 and 33 are attached to opposite ends of the weight and moving the toy by one or the other of the cords is adapted to shift the weight and operate the respective sounding devices as will be understood.

It will of course be understood that the accompanying drawing is only for the purpose of illustrating the principle of the invention, the scope of which is defined by the appended claims. The toy is provided with movable parts adapted to be operated by the rollers 4, 13, 26 and 27, the movable parts being illustrated as wings and feet in Figs. 1 to 5 and as noise-making parts in Fig. 6. The rollers 4, 13, 26 and 27 can be made to operate any desired mechanisms on the toy and the rollers can be brought into operation by any desired means and in any desired manner.

I claim:

1. A figure toy comprising the combination of a body member having movable parts, means mounting the member for traveling movement on a support, a pair of rollers adjacent the said means, one of said rollers being normally out of engagement with the support, two different toy-part moving mechanisms respectively connected to and adapted to be operated by the rotation of the rollers, and means for optionally bringing one or the other of the said rollers into engagement with the support in a manner cooperating with the first mentioned means to movably support the toy and operate the said mechanism connected to the engaged roller as such roller is rotated by movement of the toy along the support.

2. A figure toy comprising the combination of a body member having movable parts, means mounting the member for traveling movement on a support, rollers respec-

tively at opposite sides of the said means, one of said rollers being normally out of engagement with the support, two different toy-part moving mechanisms respectively connected to and adapted to be operated by the rotation of the rollers, and a weight carried by the toy and adapted to be moved to positions bringing one or the other of the said rollers into engagement with the support in a manner cooperating with the first mentioned means to movably support the toy and operate the said mechanism connected to the engaged roller as such roller is rotated by movement of the toy along the support.

3. A figure toy comprising the combination of a body member having movable parts, means mounting the member for traveling movement on a support and so disposed as to substantially balance the toy thereabout, rollers respectively at opposite sides of the said means and adapted to cooperate therewith to carry the toy, the rollers and means being so related that the toy is supported by the said means and one or the other of the said rollers, toy-part moving mechanism connected to and adapted to be operated by the rotation of the rollers, and a weight carried by the toy and adapted to be moved to positions bringing one or the other of the said rollers into cooperating supporting relation with the said means on the support.

4. A figure toy comprising the combination of a body member having movable parts, means mounting the member for traveling movement on a support, two different toy-part moving mechanisms carried by the toy, means for manually moving the toy and movable means carried by the toy and adjustable through the last named means to optionally cause one or the other of the said mechanisms to be operated as the toy is moved along the support.

5. A figure toy comprising the combination of a body member having movable parts, means mounting the member for traveling movement on a support, a pair of rollers adjacent the said means, one of said rollers being normally out of engagement with the support, two different toy-part moving mechanisms respectively connected to and adapted to be operated by the rotation of the rollers, a weight carried by the toy and adapted to be moved to positions bringing one or the other of the said rollers into engagement with the support, and a cord connected to the weight and adapted to move the weight to the said positions.

6. A figure toy comprising the combination of a body member having movable parts, means mounting the member for traveling movement on a support, a pair of rollers adjacent the said means, one of said rollers being normally out of engagement

with the support, two different toy-part moving mechanisms respectively connected to and adapted to be operated by the rotation of the rollers, means for manually moving the toy along the support, and means operated by the last said means for optionally bringing one or the other of the said

rollers into engagement with the support in a manner operating one or the other of said mechanisms as the toy is moved along the support. 10

In testimony whereof I affix my signature.

LAWRIE L. WITTER.
